BATTERY TERMINAL

Liccio Levi, Brooklyn, N. Y.

Application May 17, 1933, Serial No. 671,425

6 Claims. (Cl. 173—259)

The invention relates in general to an electric terminal and particularly relates to a terminal adapted to be applied to the binding post of a storage battery; and the invention specifically relates to that form of battery post connection which is designed to deter or prevent the formation of corrosion at the connection for the terminal posts of storage batteries.

It has been known heretofore in devices of this character to provide means for preventing the seepage of corroding acids from the battery upwardly along the battery posts; but it has been generally true that such known devices possess certain disadvantages among which might be noted that they position the acid repellent material, which is usually a dielectric, between the battery post and the cable terminal which is usually clamped thereto. The presence of this dielectric more or less interferes with the desired 20 providing of a maximum area of electric contact between the post and its associated terminal.

Accordingly, one of the objects of this invention is to provide a simplified means for locating a relatively small quantity of the corrosion repellent material at that point where it will do the greatest amount of good, and at the same time maintain the largest possible area of electric contact between the post and its associated cable.

Another feature of the invention herein is to provide a terminal structure which will retain the advantages inherent in known approved commercial forms of terminals, and provide the advantages herein recited simply by making a slight and inexpensive modification of such known forms of battery terminals.

Broadly, the invention contemplates the providing of a groove in the wall of the usual split clamping ring forming part of the terminal, locating the material containing groove at or adjacent the lower face of the ring which engages the top of the battery casing in such way as to locate a ring of small cross section of material close to the joint between the battery post and the top of the battery casing.

The invention contemplates other refinements; such for instance, as the providing of a constricted annular passageway leading downwardly from the groove, so as to permit a leakage therefrom of the material to the joint; and the disclosure also features the providing of a readily accessible passageway for replenishing the material in the groove without necessity of breaking the electric connection between the terminal and post.

Various other objects and advantages of the invention will be in part obvious from an inspec-

tion of the accompanying drawing and in part will be more fully set forth in the following particular description of one form of mechanism embodying the invention, and the invention also consists in certain new and novel features of construction and combination of parts herein-after set forth and claimed.

In the accompanying drawing:

Fig. 1 is a view of a conventional form of storage battery shown in side elevation with a terminal connection in operative engagement therewith, shown partly in vertical section and showing a preferred embodiment of the invention;

Fig. 2 is a plan view looking down upon the disclosure in Fig. 1, with parts broken away to show internal construction and parts taken on line 2—2 of Fig. 1; and

Fig. 3 is a vertical, sectional view taken on the line 3—3 of Fig. 2 looking in the direction indicated by the arrow.

In the drawing there is shown a storage battery 10 with its cell casing 11 and top member 12 through which extends a frusto-conical terminal post 13. The post is engaged by a somewhat conventional form of split clamping ring 14 bifurcated to form bolt flanges 15 and 16 through which is threaded a clamping bolt 17 secured by nut 18 so as to bring the clamping ring in snug engagement with the terminal post 13 as is usual in such constructions. Also following conventional forms, the ring 14 is provided with a cable socket 19 into which is fitted the lead or cable 20.

The ring portion of the terminal is provided with a bore 21 of conventional frusto-conical form to fit the post 13 and still following conventional structures, the ring is positioned on the post with its underside 22 actually engaging the top member 12, or in juxtaposition thereto, in either case providing a slight clearance 23 due to the fact that the top of the member 12 and the face 22 are usually formed rough and unfinished so that a clearance, however slight and irregular, is almost bound to exist.

The feature of this disclosure is that the lower portion of the wall forming the bore 22 is recessed to provide an annular groove 24 which faces the lower end of the exposed portion of the post 13 and is designed to contain a ring 25 of corrosion repellent material, usually a form of grease or oil commonly employed for the purpose of defeating the tendency of the acid in the battery from creeping upwardly along the post and causing corrosion of the metallic parts forming the battery connection.

The ring is also provided with a material feeding passageway 26 which leads from the top surface 27 of the ring downwardly and inclined slightly inwardly towards the post 13. The passageway opens at its lower end 28 into the upper side of the groove 24. In the illustrated form of the invention the passageway 26 is disposed at the crotch portion of the ring and between the bore 21 and the cable sockets 19 as this provides a convenient place for locating the passageway and its presence does not tend to weaken the structure of the ring. While the groove 24 may be contained entirely in a horizontal plane, it is herein suggested that the opposite ends 29 and 30 may be curved upwardly from the plane containing the major portion of the groove, so as to direct any material which may be discharged from the ends of the groove on to the bolt 17 at its juncture with the bolt flanges as it is at these points that corrosion is quite apt to form.

A further refinement of the basic structure is the providing of an annular constricted leaking passageway at 31 between the groove 24 and the lower face 22 of the ring. As illustrated in Fig. 3, the groove 24 and leaking passageway 31 may be formed by machining the lower end of the ring bore to give the outer outlining wall 32 a form somewhat S-shaped thus providing rounded surfaces along which the material may creep as it moves slowly from the ring-like reservoir at 24 to the joint 33 between the top member 12 and the post 13.

By means of a device of the character disclosed it is possible to clamp the cable terminal to the battery post, tightening up the connection by means of the nut 18 until a long snug engagement is provided between the portion of the ring above the groove and the adjacent portion of the post. Then by introducing the desired material through the passageway 26, the groove 24 is eventually filled with the material and from time to time fresh material may be introduced through the passageway 26 to replenish that which may have drained out of the groove. This can be attained without necessity of breaking the initially formed electric connection between the terminal and post. Due to the vibration of the parts when mounted on an automobile and even in the absence of any such vibratory movement the corrosion repellent material will eventually creep from the groove reservoir provided by the groove 24 downwardly to the joint 33 and may even spread therefrom outwardly and radially through the clearance 23. In this way the material is permitted to seep across the lower face of the connection and around the base of the post 13.

Various modifications can be made as desired, for instance, a source of supply such as an oil reservoir may be secured in place to supply the passageway 26 and in those cases where access cannot be provided to passageway 26 from the top of the terminal, the passageway may lead from the side rather than the top of the ring 14. In this way it is possible to maintain a constantly replenished supply of clean material to that portion of the connection where it is needed, that is, particularly to the joint at 33.

It is obvious that no other change need be made to the conventional form of terminal herein illustrated, except to form the groove 24 and if desired to form the leaking passageway 31, and to drill the supply passageway 26, both of which operations are extremely simple and can be easily performed as a factory manufacturing

proposition without materially adding to the initial expense of forming the terminal.

While there have been shown, described and pointed out in the annexed claims, certain novel features of the invention, it will be understood that various omissions, substitutions and changes in the form and details of the device illustrated and in its operation may be made by those skilled in the art without departing from the spirit of the invention.

I claim:

1. In a device of the class described, the combination of a storage battery provided with a top member and a terminal post projecting above the top member and of frusto-conical form with its wider end at the top member, a split clamping ring having a bore fitting the post, in snug electric contacting engagement therewith for the major portion of its length and having its lower face disposed in contact with or at least in close juxtaposition to the top member, the portion of the bore adjacent the lower face of the ring provided with a groove for containing a corrosion deterrent material and for locating the material adjacent the bottom and spaced from the top of the post, the portion of the bore between the groove and the lower face of the ring providing a restricted annular passageway permitting the material to leak from the groove downwardly to the joint between the top member and the post, and said ring provided with a material feeding passageway, leading from the top of the ring in spaced relation to the post downwardly and inclined towards the post and opening into the groove.

2. In combination, a storage battery including a top member and a terminal post projecting upwardly through said member, a conductor terminal attached to the upper portion of said post and including a bore receiving the post, said terminal disposed with its underside disposed close to the top surface of the said member to form a thin joint therebetween, the bore provided adjacent its lower end with an annular groove open to the portion of the post just above said top member and the bottom of the groove opening through a constricted annular passage to the joint between the post and top member.

3. A terminal attachment for storage batteries comprising a ring having a bore to receive the battery terminal post, said ring having a groove in the wall of its bore and adjacent one end of the bore, the portion of said bore between the groove and the adjacent end being slightly enlarged to provide a constricted passageway leading longitudinally of the bore from the groove to the adjacent end of the bore.

4. A terminal attachment for storage batteries comprising a ring having a bore of frusto-conical form to receive the battery terminal post, the larger end of the bore defined by a groove in the wall thereof, said groove being substantially S-shaped in radial cross section and said ring provided with a passageway spaced from the bore and leading into the groove.

5. A terminal attachment for storage batteries comprising a split ring with the ends thereof forming bolt flanges, a clamping bolt passed through the flanges, the bore of the ring provided with an annular groove, the ends of the groove extending upwardly from the plane of the major portion of the groove to direct the contents of the groove towards the clamping bolt and said ring provided adjacent its crotch portion with a downwardly inclined passageway with its up-

per end accessible from the top face of the ring and its lower end opening into the groove.

6. A terminal attachment for storage batteries comprising a split ring with the ends thereof forming bolt flanges, a clamping bolt passed through the flanges, the bore of the ring pro-

vided with an annular groove, the ends of the groove extending upwardly from the plane of the major portion of the groove to direct the contents of the groove towards the jointures between the clamping bolt and the bolt flanges.

LICCIO LEVI.
